Primary Examiner—Sam Rosen*Attorney, Agent, or Firm*—Lawrence I. Lerner[57] **CLAIM**

The ornamental design for a right and left-hand pistol safety lock set, as shown.

DESCRIPTION

FIG. 1 is an exploded perspective view of a right and

left-hand pistol safety lock set embodying my new design;

FIG. 2 is a right side elevational view of the right-hand pistol safety lock illustrated in FIG. 1;

FIG. 3 is a left side elevational view of the safety lock of FIG. 2;

FIG. 4 is a back elevational view of the safety lock of FIG. 2;

FIG. 5 is a front elevational view of the safety lock of FIG. 2;

FIG. 6 is a top plan view of the safety lock of FIG. 2; FIG. 7 is a bottom plan view of the safety lock of FIG. 2;

FIG. 8 is a perspective view of the left-hand pistol safety lock shown in FIG. 1;

FIG. 9 is a front elevational view of the safety lock of FIG. 8;

FIG. 10 is a back elevational view of the safety lock of FIG. 8;

FIG. 11 is a left side elevational view of the safety lock of FIG. 8;

FIG. 12 is a right side elevational view of the safety lock of FIG. 8;

FIG. 13 is a bottom plan view of the safety lock of FIG. 8; and

FIG. 14 is a top plan view of the safety lock of FIG. 8;

FIG. 9

FIG. 11

FIG. 12

FIG. 13
